UNITED STATES PATENT OFFICE.

LAURENCE A. HAWKINS, OF SCHENECTADY, NEW YORK, ASSIGNOR, BY MESNE ASSIGNMENTS, TO THE UNION SWITCH AND SIGNAL COMPANY, A CORPORATION OF PENNSYLVANIA.

CONTROL OF SIGNAL-LAMPS.

1,090,301.

Specification of Letters Patent. Patented Mar. 17, 1914.

Application filed November 20, 1911. Serial No. 661,411.

To all whom it may concern:

Be it known that I, LAURENCE A. HAWKINS, citizen of the United States, residing at Schenectady, in the county of Schenectady and State of New York, have invented certain new and useful Improvements in the Control of Signal-Lamps, of which the following is a specification.

My invention provides a means for the control of electric lamps over an alternating current transmission line, without the use of line wires other than those comprised in the transmission line.

My invention is particularly adapted to the control of the electric lamps used in railway systems from a central point, such as from a station from which power is supplied to the signaling system. Thus the lamps over a large territory may be controlled from a central point, current being turned on to the lamps in the evening and turned off in the morning, thereby prolonging the life of the lamps and avoiding the unnecessary use of current for illuminating the lamps during daylight.

I will describe my invention as applied to two forms of transmission lines used for railway signaling purposes, and will then point out the novel features thereof in the claim.

In the accompanying drawings, Figure 1 is a diagrammatic view showing a railway signaling system supplied from a single phase transmission line, and having a system for the control of the signal lamps embodying my invention applied thereto. Fig. 2 is a view similar to Fig. 1 but showing a system embodying my invention applied to a railway signaling system supplied from a polyphase transmission line.

Similar reference characters refer to similar parts in each of the views.

Referring particularly to Fig. 1, the numerals 4, 4 designate two lines of railway track over which traffic is governed respectively by two railway signals S and S'. These signals may be of any type and may be controlled in any suitable manner, these features forming no part of my invention. As is well known, the daylight indication of a railway signal is usually given by the position of a semaphore arm, and the night indication by a light. 8 and 9 designate electric lamps for the night indication of signals S

and S' respectively. 22 designates a single phase transmission line which furnishes energy to the various parts of the signaling system such as the signal mechanisms, track circuits, etc. This line is connected with a source of current 23 through a transformer 24; 25 designates a transformer located adjacent the signals S and S', from which current is supplied to these signals and to the adjoining track circuits.

In my invention I provide an auxiliary circuit for the control of the signal lamps, one side of which circuit is formed by the transmission line 22 and the other side by a suitable return conductor, herein shown as being the ground. The transmission line is employed as one side of this auxiliary circuit by means of the following arrangement:—The middle point of the secondary of transformer 24 is connected with ground by means of a conductor 13, and the middle point of the primary of transformer 25 is similarly connected with ground by means of a conductor 14. Interposed in the conductor 13 are a source of current M (here shown as being a separate generator) and a circuit controller 16. Interposed in the conductor 14 is a magnet 17 provided with an armature 18. The location of the transformer 24 and conductor 13 may be termed a point of control, since it is the point from which the signal lamps 8 and 9 are controlled. Lamps 8 and 9 are supplied with current from the transformer 25, the circuit for these lamps being as follows—from the secondary of the transformer through wires 10 and 11, lamps 8 and 9, wire 28 to the transformer. Interposed between wires 10 and 11 is a circuit controller 12. 19 designates a ratchet wheel operated by armature 18 in the manner clearly shown in the drawings. Operatively connected with the ratchet wheel is a cam wheel 20 which operates the circuit controller 12 through the medium of a link and roller 21. The construction is such that successive operation of the armature 18 will move the cam wheel 20 to such positions as to alternately open and close the circuit controller 12.

The operation of the system is as follows—When it is desired to illuminate the lamps 8 and 9, the circuit controller 16 is momentarily closed, thereby causing magnet 17 to close circuit controller 12. When it is

desired to extinguish the lamps, circuit controller 16 is again momentarily closed, causing magnet 17 to open circuit controller 12. It will be noted that current is consumed by 5 the magnet 17 only at such time as an operation of circuit controller 12 is desired, and then only for a moment of time.

In the system shown in Fig. 2, the transmission line 1 is of the three-phase three-wire type, and the conductors 13 and 14 are connected with the neutral points of star 10 transformers 3 and 7 respectively. Transformer 3 is supplied with current from a three-phase generator 2. As here shown, 15 the auxiliary circuit is supplied with current from a secondary winding 15 in the transformer 3, although it is understood that an exterior source of current may be equally well employed as in Fig. 1. While 20 the transformers at the generating station or control point are indicated diagrammatically as connected in Y or in star, I have shown for illustrative purposes the transformers at the signal location connected in 25 T, or in other words, with the well known three-phase two-phase connection. However the transformers are connected, the connection of the control circuit thereto should be made at the neutral point, which 30 is always the geometric center of the triangle formed by the terminals of the transformer primary windings. The remaining parts of the system shown in Fig. 2 are 35 the same as those in Fig. 1, hence no further explanation is required.

Although I have herein shown a control system embodying my invention applied to

only one signal location, it is understood that each signal location may be provided with an electromagnet 17 and the circuit 40 controlling apparatus operated thereby; the lamps for all the signals will then be alternately illuminated and extinguished by successive operations of the circuit controller 16 at the power house. 45

It is understood of course that a lamp control system embodying my invention may be applied to a railway having any number of tracks and any arrangement of signals.

Although I have herein shown and described only one form of lamp control system embodying my invention, it is understood that various changes and modifications may be made therein within the scope of the appended claim without departing 55 from the spirit and scope of my invention.

Having thus described my invention, what I claim is:—

In railway signaling, a transmission line, 60 transformers distributed along the line for supplying the signaling apparatus with current, electric lamps for the signals, means for connecting and disconnecting each lamp to and from the secondary of an adjacent transformer, and a control circuit for said means including the conductors of the transmission line and a controlling device located at a distant point.

In testimony whereof I affix my signature 70 in presence of two witnesses.

LAURENCE A. HAWKINS.
